UNITED STATES PATENT OFFICE.

OLIVER G. SIMMONS, OF LAKEWOOD, OHIO, ASSIGNOR TO THE NATIONAL TOOL COMPANY, OF CLEVELAND, OHIO.

VALVE SEATING AND ALIGNING TOOL.

Application filed September 9, 1926. Serial No. 134,492.

My invention relates to improved means for reaming the valve stem holes and valve seat in alignment therewith in the cylinder blocks or cylinder heads of internal combustion engines.

The main object of the invention resides in the means provided for guiding the valve seat reaming cutter in perfect alignment with the valve stem reamer.

Another object of the invention is to provide a valve stem reamer of tool steel, preferably high speed steel, and fixedly secured to a body portion of less expensive low carbon machine steel.

A further object of the invention is to provide the aligning portion in the form of a port cutter and the chamfering cutter, detachably secured to the body portion, to remove excess metal from the valve seat surface, adapting a valve seating cutter in a subsequent operation to be detachably secured to the body portion adapted to ream the valve seat.

A still further object of this invention is to provide a pin detachably secured to the body portion, adapting this valve seating and aligning tool to be manually operated to recondition cylinder blocks and cylinder heads in service stations.

Heretofore in valve seating tools of this character it has been the practice to provide a valve stem reamer and a valve seating cutter with no special means for aligning the valve seating cutter with the valve stem reamer, with a result that when a cylinder block or cylinder head was reconditioned in a service station, by a manually operated tool of the character referred to, the valve seating reamer was invariably sprung and produced an elongated valve seat with consequent leakage from the combustion chamber and a consequent reduction of power due to the inefficient operation of the motor.

The valve port aligning cutter of the present invention, therefore, serves as a guide for the valve cutter, and a valve seat reconditioned by the manually operated tool of the present invention, produces concentric valve seats and a consequent efficient operation of the motor, since no gases during the combustion period are permitted to escape from the cylinder.

With the above and other objects in view the invention comprises broadly the valve aligning feature, obtained by the structure

illustrated in the accompanying drawings hereinafter described and particularly set forth in the appended claim, together with such variation and modification thereof as will be apparent to those skilled in the art to which the invention appertains. Reference should be made to the accompanying drawings forming a part of this specification.

Fig. 1, is a view of the valve seating and aligning tool with a valve seating cutter and a valve chamfering cutter detached therefrom.

Fig. 2, is a view in elevation of the valve seating cutter.

Fig. 3, is a bottom view of the valve seating cutter shown in Fig. 2. In this view the teeth of the valve reamer are clearly seen to be unevenly spaced.

Fig. 4, is a view in elevation of the chamfering cutter.

Fig. 5, is a bottom view showing the teeth of the chamfering cutter of Fig. 4.

Fig. 6, is a fragmentary portion of the valve aligning tool showing the valve stem reamer, the port aligning cutter and the valve seat cutter.

Fig. 7, is an end view of Fig. 6.

Fig. 8, is similar to Fig. 6, except in this view the chamfering cutter has been substituted for the valve seating cutter.

Fig. 9, is an end view of Fig. 8.

Fig. 10, is a view in elevation, partly in section, of the valve seating and aligning tool as it appears when inserted in a cylinder block, after all operations have been completed to ream the valve stem hole and finish ream the valve seat. The aligning feature of this manually operated tool is shown in the form of a port cutter and clearly illustrates its aligning feature, maintaining concentricity between the valve seat reamer and the valve stem reamer shown in the fragmentary section of the valve seat of the cylinder block.

Fig. 11 is a fragmentary section of the valve seat of the cylinder block illustrating the form produced by the chamfering cutter and its relation to the valve seat of the cylinder block.

Fig. 12 is a fragmentary sectional view of the valve seat of the cylinder block as it would appear after the chamfering cutter had operated and cut away the valve seat.

The body portion 1, is provided with the detachable stem 2, shown. The lower por-

tion 3 of the body portion 1 is tapered and is provided with detachable pins 4 and 5 for a purpose to be later described. In the tapered portion 3 of the body 1, a hole 6 is provided, adapting an end portion of the reamer 7 to be firmly secured to said body portion 1, for example, by shrinking the end portion of reamer 7 into the hole in tapered portion 3; thus the body portion 1 may be made of inexpensive low carbon machine steel and the reamer portion 7 may be made of high speed steel or of high carbon tool steel.

The port cutter member 8 is provided with a tapered hole 9 and a milled slot 10, adapting said port cutter to fit the tapered end 3 and the pin 5; the pin 5 fitting into the milled slot 10, so that as the stem 2 is grasped by the operator to rotate same the port cutter member 8 will be rotated with it.

The port cutter 8 is provided with teeth 11, chamfered slightly on the front edge, as shown at 12, to provide a cutting edge. The body portion proper, however, is concentrically ground with the taper hole 9, thus as the edge 12 is rotated in the direction of the arrow 13 and a slight pressure exerted in the direction of the arrow 14, the port cutter 8 will remove metal in the upper part of the cylinder block and the concentrically ground feature of the body portion of said cutter will serve to guide it truly in a concentric path, with respect to the teeth 15 of the valve stem reamer 7.

Referring to Fig. 4, the chamfering cutter 16 is provided with the teeth 17, tapered hole 18 and milled slot 19, adapting it to be detachably secured to the tapered portion 3 of the body portion 1. To place this chamfering tool on the body portion 3, it is necessary to remove the port cutter 8 and the pin 5. These are easily removed by means of a slight blow from a wooden mallet, and the chamfering cutter inserted, the milled slot 19 being lined up and adapted to receive the pin 4, after which the pin 5 is inserted and the port cutter placed in position shown.

The valve seat cutter 20 is shown in Fig. 2. This is provided with milled slot 21, tapered hole 22, adapting this cutter to fit the tapered portion 3, and pin 4 in a manner similar to chamfering cutter 16. The teeth 23 of the valve cutter 20 are unevenly spaced as shown in Fig. 3, so that as the valve seat cutter 20 is rotated, the teeth being unevenly spaced, chatter will not result and therefore insures a smooth seat for the valve.

The lower portion 24 of the valve stem reamer 7 indicates that the teeth are not milled clear to the end of same. This lower portion 24 is ground concentric a few thousandths smaller in diameter than the diameter of the portion of the teeth 15, so that the stem 24 will serve as a guide when entering the valve stem reamer. This is shown

in Figs. 1 and 8. In Figs. 6 and 10, however, the teeth 15 are milled clear to the end 25 of the valve stem reamer 7. This is done to provide chip clearance when an oversize valve is to be used and when the reamer is designed this way, .015 inch of metal is usually removed for the reason that oversize valve stems are made substantially .015 inch over the size of the valve stem originally furnished with the motor and if the teeth were not cut clear through to the end 25, the chips would pack up and make the tool inoperative. Figs. 6 and 10, therefore, illustrate the tool when adapted to be used for oversize valves, whereas Figs. 1 and 8 illustrate the reamer for use with standard valve stem as furnished originally with the motor.

Fig. 6 shows the set-up of the valve cutter 20 in place, whereas Fig. 8 shows the assembly of the chamfering cutter 16, the method of application having been previously described.

In the use of the tool the following procedure is followed:

Chamfering cutter 16 is placed as shown in Fig. 8. The port cutter 8 in position, the operator inserts the reamer portion 7 in the hole of the valve stem portion 26, see Fig. 10, and begins to rotate the tool as previously described exerting slight pressure in the direction of the arrow 14. This will cause the reamer to work its way into the valve hole until port cutter 8 reaches the point 27, Fig. 12, when it will begin to cut and remove metal from the surface 28 of the port hole. The port cutter 8 being concentrically ground will seat itself as shown in Fig. 10, and will, therefore, act as a guide to maintain alignment for the chamfering cutter 16 which chamfers the surface 29 as shown in Fig. 12. After this operation the valve seat cutter 20 is inserted, as shown in Fig. 6, and the tool again entered into the valve stem hole, as shown in Fig. 10, and operated as previously described to cut the valve seat portion 30, as shown in Fig. 11. It is important that the width W, Fig. 11, of the valve seat be substantially the same in all cylinders and this is made possible by virtue of the chamfering cutter 16 previously described.

Having thus described my invention, I claim:

In a valve seating tool, body portion provided with a valve stem reamer cutter, a detachable chamfering cutter and a detachable port cutter interposed between the cutters aforesaid, said port cutter being concentrically ground and serving as a guide to maintain alignment between said chamfering cutter and said valve stem reamer cutter.

Signed this 7th day of September, 1926.
OLIVER G. SIMMONS.
